CLAIM

The ornamental design for a pistol magazine as shown and described.

DESCRIPTION

FIG. 1 is a right upper perspective view of the pistol magazine showing our new design;

FIG. 2 is a left upper perspective view thereof;

FIG. 3 is a right lower perspective view thereof;

FIG. 4 is a rear perspective view thereof;

FIG. 5 is a front view thereof;

FIG. 6 is a right side view thereof;

FIG. 7 is a left side view thereof;

FIG. 8 is a rear view thereof;

FIG. 9 is a top view thereof; and,

FIG. 10 is a bottom view thereof.

The broken lines and the unshaded areas adjacent to them illustrate portions of the pistol magazine that form no part of the claimed design.

1 Claim, 7 Drawing Sheets
